UNITED STATES PATENT OFFICE.

JOHN H. SHEPPARD, OF WORCESTER, MASSACHUSETTS.

SHEAR-GRINDER.

1,126,891.

Specification of Letters Patent.

Patented Feb. 2, 1915.

Application filed February 27, 1914. Serial No. 821,526.

To all whom it may concern:

Be it known that I, JOHN H. SHEPPARD, a citizen of the United States, residing at Worcester, in the county of Worcester and Commonwealth of Massachusetts, have invented a new and useful Improvement in Shear-Grinders, of which the following, together with the accompanying drawing, is a specification.

My invention relates to shear grinders and more particularly to that form of shear grinder in which a shear blade is clamped or supported in proper predetermined position while being sharpened.

One object of the invention is to provide a shear grinder having means for supporting a shear blade in proper angular position with relation to the grinding or abrading means so as to insure a proper predetermined angle at the cutting edge of the blade.

Another object of the invention is to provide a shear blade support adapted to cause the blade to travel across the face of the abrading means while the blade is being ground so as to distribute the wear as evenly as possible and not wear a groove in the face of the abrading means.

Another object of the invention is to provide an abrading wheel rotatable about an axis inclined to the path of the shear blade so as to act at a slight angle to the cutting edge of the blade rather than directly along it.

Another object of the invention is to make the various parts of the grinder adjustable so as to adapt it for use with various sizes and types of shears and so as to permit the user to vary its action upon a shear blade as desired.

Other objects and advantages will appear from the following description taken in connection with the accompanying drawing, in which—

Figure 1 is a side view of a shear grinder constructed in accordance with my invention, a pair of shears being shown in position to be sharpened; Fig. 2 is a plan view of the grinder and shears shown in Fig. 1;

Fig. 3 is a view of the grinder and shears from the side opposite that shown in Fig. 1; and Fig. 4 is a detail view of the edge of the abrading wheel and a section of the blade resting upon it.

Like reference characters refer to similar parts in the different figures.

The grinder shown in the drawing includes a frame 1 supported upon legs 2.

In the upper portion of the frame is formed a bearing 3 in which turns a shaft 4 carrying an abrading wheel 5, the abrading wheel being secured between a shoulder 7 on the shaft and a pair of nuts 8 threaded onto the end of the shaft. The opposite end of the shaft is provided with a small hand wheel 9, by means of which the shaft may be held while the nuts 8 are being tightened or loosened.

A longitudinally reciprocatory slide 10 is guided in suitable ways 11 formed in the frame 1. The slide 10 is formed with a rack 12 which drives a pinion 13 and a gear 14 fixed to the same shaft 15 that carries the pinion. The gear 14 drives the abrading wheel 5 by means of a pinion 16 fixed to the shaft 4 with the abrading wheel.

An angle piece 17 is adjustably secured to one end of the upper edge of the reciprocatory slide 10 by means of a thumb screw 18 passing through a slot 19 in the angle piece 80 and threaded into the frame.

A plate 20 having a pair of spaced upstanding lugs 21 is adjustably secured to the upper face of the angle piece 17 by means of a thumb screw passing through a slot 23 in the plate and threaded into the angle piece. One end of a heavy wire 24 is pivoted in the lugs 21 and retained in place by a cotter pin 25. The other end of the wire 24 is bent at a right angle, and pivotally supported between a pair of cotter pins on this end of the wire is a clamp 26, a set screw 27 being provided to secure the clamp in adjusted angular position about the wire. The clamp 26 is of inverted U-shape so as to receive one blade 28 of a pair of shears and support it in proper position to be sharpened by the abrading wheel 5. A thumb screw 29 passes through the leg of the clamp 26 which is pivoted upon the wire 24 and secures the blade 28 of the shears firmly in place by pressing it against the inner face of the opposite or free leg of the clamp as shown in Fig. 2.

A stop 30 is adjustably secured to the slide 10 by means of a thumb screw 31 so as to limit motion of the slide in one direction at any desired point as determined by the

length of the shear blade being sharpened. A shoulder 32 formed on the slide 10 serves to limit motion of the slide in the other direction.

5 A projection 33 secured to the stop 30 by a set screw 34 is bent horizontally at its upper end to which is pivoted a weight 35 adapted to rest upon a shear blade being sharpened and press it against the abrading 10 wheel.

One end of the slide 10 is provided with a finger hole 36 so that it may be conveniently grasped and reciprocated in order to drive the abrading wheel and move the shear 15 blade back and forth along its surface.

A small cup 37 is provided to hold water into which the abrading wheel may dip while in use.

When the parts of the grinder are in 20 proper adjustment, the inner face of the free leg of the clamp 26 is inclined slightly so as to tip the inner face of the shear blade being sharpened, thus giving the proper angle to the cutting edge of the blade as indicated in Figs. 2 and 4. Adjustment of the plate 20 allows the shear blade to assume a position at an angle to the path of motion of the slide, as shown in Fig. 2, so as to cause the blade to travel back and forth along the 30 face of the abrading wheel. This distributes the wear on the wheel and prevents the formation of grooves. Adjustment of the angle piece 17 vertically permits the shear blade 28 to be supported in a substantially horizontal position so as to move 35 properly along the surface of the abrading wheel. Adjustment of this same angle piece 17 angularly about the thumb screw 18 permits longitudinal adjustment of the shear 40 blade 28 so that the abrading wheel will reach the inner end of the blade. The stop 30 is adjusted to stop the slide 10 just as the abrading wheel reaches the extreme outer end of the blade.

45 The outer or free leg of the clamp 26 is beveled at its forward edge 38 so as to press against the blade 39 of the pair of shears and hold it away from the abrading wheel while the blade 28 is being sharpened.

50 While I have shown and described the details of one form of my invention, I do not wish to be limited to such details as changes may be made without departing from the spirit of the invention; but—

55 Having described my invention, what I claim as new and desire to secure by Letters Patent is:

1. A shear grinder including an abrading wheel, a reciprocatory support for holding 60 a shear blade against the peripheral surface of the abrading wheel, and means for rotating the abrading wheel in a plane inclined to the path of the blade and its support.

2. A shear grinder including an abrading 65 wheel, a reciprocatory support for holding a shear blade against the peripheral surface of the abrading wheel and means actuated by the support and including a gear wheel and a set of gear teeth meshing therewith for rotating the gear wheel, the plane of rotation of the gear wheel being inclined to the path of said set of gear teeth to permit the abrading wheel to be rotated in a plane inclined to the path of the support 70 and shear blade.

3. A shear grinder including an abrading wheel, a reciprocatory support for a shear blade, and yielding means for pressing the blade against the abrading wheel. 80

4. A shear grinder including an abrading wheel, a reciprocatory support for a shear blade, and a weight pivotally connected to the support to rest upon the blade and press it against the abrading wheel. 85

5. A shear grinder including an abrading wheel, a reciprocatory support for a shear blade, a stop attached to the support to limit the extent of its motion, and a weight pivotally connected to the stop to rest upon 90 the blade and press it against the abrading wheel.

6. A shear grinder including an abrading wheel, a universally adjustable support for a shear blade, and means for causing relative reciprocatory motion between the abrading wheel and support. 95

7. A shear grinder including an abrading wheel, and a reciprocatory support for holding a shear blade against the peripheral surface of the abrading wheel, the support being adjustable to vary the angle between the blade and its line of motion in a plane substantially tangent to the abrading wheel at its point of contact with the shear blade. 100

8. A shear grinder including an abrading wheel, a reciprocatory support for a shear blade, the support having a face to contact with the inner face of the blade and hold it at a predetermined inclination to the face 110 of the abrading wheel.

9. A shear grinder including an abrading wheel, and a reciprocatory support to hold a shear blade at an angle to the line of motion of the support, whereby the blade will 115 travel across the face of the abrading wheel as it is reciprocated with its support.

10. A shear grinder including an abrading wheel, and a reciprocatory support to hold a shear blade at an angle to the line of motion of the support, whereby the blade will travel across the face of the abrading wheel as it is reciprocated with its support, the support being adjustable to vary the angle between the shear blade and the line 125 of motion of its support.

11. A shear grinder including an abrading wheel, and a reciprocatory support for

one blade of a pair of shears, the support being formed to hold the other blade away from the abrading wheel while the first blade is being sharpened.

5 12. A shear grinder including an abrading wheel, and means for supporting one blade of a pair of shears in position to be

sharpened by the abrading wheel and for holding the other blade away from the abrading wheel.
